CLAIM

The ornamental design for a drawer pull, as shown and described.

DESCRIPTION

FIG. 1 is a front, bottom, first side, isometric view of a drawer pull embodying the new design, in accordance with a first embodiment;

FIG. 2 is a rear, top, second side, isometric view thereof; FIG. 3 is a front view thereof;

FIG. 4 is a rear view thereof;

FIG. 5 is a second side view thereof;

FIG. 6 is a first side view thereof;

FIG. 7 is a top view thereof; and

FIG. 8 is a bottom view thereof.

FIG. 9 is a front, bottom, second side, isometric view of a drawer pull embodying the new design, in accordance with a second embodiment;

FIG. 10 is a rear, top, first side, isometric view thereof;

FIG. 11 is a front view thereof;

FIG. 12 is a rear view thereof;

FIG. 13 is a second side view thereof;

FIG. 14 is a first side view thereof;

FIG. 15 is a top view thereof; and,

FIG. 16 is a bottom view thereof.

Broken lines are used to illustrate portions of the drawer pull that form no part of the claimed design.
